UNITED STATES PATENT OFFICE.

FRANCOIS J. SCHAEZEL, OF STAPLETON, NEW YORK, ASSIGNOR TO PACIFIC MILLS,
OF BOSTON, MASSACHUSETTS, A CORPORATION OF MASSACHUSETTS.

DESIGN FOR TEXTILE FABRIC OR WALL-PAPER.

42,245.

Specification for Design.

Patented Feb. 27, 1912.

Application filed December 14, 1911. Serial No. 665,836. Term of patent 3½ years.

To all whom it may concern:

Be it known that I, FRANCOIS J. SCHAEZEL, a citizen of the United States, residing at No. 18 Theresa Place, Stapleton, Staten Island, in the State of New York, have invented a new, original, and ornamental Design for Textile Fabrics or Wall-Papers, of which the following is a specification, reference being had to the accompanying drawing, forming part thereof.

The drawing is a plan view of a portion of a textile fabric or wall paper showing my design.

I claim:

The ornamental design for a textile fabric or wall paper as shown.

FRANCOIS J. SCHAEZEL.

Witnesses:

PHILIP F. WICKSEL,
WILLIAM F. MEEHAN.
